CARBURETOR FOR OBTAINING GASEOUS MIXTURES FOR INTERNAL COMBUSTION ENGINES

Wilhelm Heinrich Gerard Wunsch and Robert Jean Achille Rolland, Brussels, Belgium; vested in the Alien Property Custodian

Application September 28, 1937, Serial No. 166,034
In Belgium September 29, 1936

5 Claims. (Cl. 48—107)

The present invention relates to carburetors used for producing gaseous mixtures for internal combustion engines.

It is well known that the gaseous mixtures intended to be introduced into internal combustion engines have been obtained hitherto by atomizing the liquid fuel in a stream of air drawn in by the engine. As a consequence the fuel is only partially vapourized, and still remains in a vesicular form, or in tiny droplets. The presence in the mixture of these tiny droplets of liquid causes various inconveniences. For example when these droplets are in the cylinders of the engine they burn incompletely and give rise to harmful carbon deposits on the internal surfaces of the cylinders, and also on the ignition devices. This not only causes fouling of the cylinders but also increases the consumption of petrol.

Furthermore the gaseous mixtures hitherto have been produced, generally speaking, by means of delicate devices such for example as spraying nozzles which have apertures of such small section that they become blocked up, relatively frequently by dirt and other impurities even of small dimensions.

One of the objects of the invention is to remedy these drawbacks and to avoid totally the stops nowadays still quite frequent as a result of the spraying nozzles being plugged up or obstructed by impurities sometimes of very small volume.

Another object of the invention is to do away almost completely with the fouling of the engine parts coming into contact with the explosive mixture, by the suppression of the incomplete combustion of the fuel droplets.

A further object is the obtainment of a perfect mixture made to suit accurately the different speeds of the engine and to attain thus a substantial saving of fuel.

Still another object is to ensure the possibility of a perfect control with simple means.

With these objects in view, our invention essentially consists in the special arrangement and combination of parts hereinafter fully described and pointed out in the appended claims.

On the annexed drawings:

Figure 1 is a vertical sectional view of a carburetor according to the invention, with a vaporizing chamber partly filled with fuel to be vaporized.

Figure 2 is a vertical section taken on a plane perpendicular to the sectional plane of Fig. 1 and

passing through the axis of the air inlet conduit to the engine.

Figure 3 is a section similar to that of Fig. 1 showing a second form of construction of the carburetor with a vaporizing chamber containing no liquid fuel.

Figure 4 shows a section, similar to that of Fig. 2, of the carburetor according to Fig. 3.

Figure 5 is a vertical section of a third form of carburetor having a preliminary vaporization chamber provided with an automatic air valve regulated by the vacuum existing in the vaporizing chamber.

Figures 6 and 7 represent respectively a projection on a horizontal plane of the upper and lower faces of the carburetor shown in Fig. 5.

Figure 8 is a vertical section, passing through the axis of the air supply pipe to the engine, of a fourth form of construction of carburetor according to the invention, having a preliminary vaporization chamber with obturators or flap valves that are not automatic, but operate mechanically.

Figure 9 is a projection on a horizontal plane of the carburetor shown in Fig. 8.

In Figs. 1 and 2, 1 indicates an hermetically closed vaporization chamber which contains a certain quantity of liquid fuel 2, kept at a constant level by means of a float 3 which controls the closure of a needle valve 4 through the intermediary of a lever 5 pivoting about an axis 6. This needle valve closes or opens a pipe 7 through which the fuel enters. A perforated plate (not shown) may be placed slightly above the level of the liquid so as to prevent the latter splashing when the vehicle is in motion.

The vaporizing chamber 1 is arranged alongside a tubular conduit 8 through which the air supply is drawn by the engine in the direction indicated, by the arrow. A regulating butterfly valve 9, fixed to a spindle 10, is capable of pivoting through a quarter of a revolution so as to close or open the section of the conduit 8 to avert or permit the passage of air to the engine.

A pipe or channel 11 bent into the direction of the engine opens into the conduit 8. The mouth 12 of the pipe 11, directed towards the engine, opens in the axis of a diffuser 13 fixed in the interior of the conduit 8. The pipe 11 provides communication between the vaporizing chamber 1 and the conduit 8.

The spindle 10 on which the butterfly valve 9 is fixed passes through the wall of the conduit 8, with slight friction but in an air-tight manner, and into the chamber 1. Its end is sup-

ported in a bearing 14 so constructed as not to allow any infiltration of air from the exterior into the interior of the vaporizing chamber 1. This spindle 10 carries a sleeve 15 to which is attached a resilient metallic part acting as the obturator 16, this metallic part being of such form, for example in the form of a sector, as progressively to uncover with its external edge the hole 17 formed by the end of the pipe 11. The oscillatory movement of the obturator 16 corresponds to that of the butterfly valve 9.

The conduit 8 terminates at the end nearest the engine in a flat part or base 18 which enables the carburetor to be fixed to the inlet manifold of the engine.

Finally the spindle 10, whose end remote from the chamber 1 also passes through the wall of the conduit 8, has fixed to it a lever arm 19 terminating in a swivel joint 20 to which the engine speed control member is adapted to be applied.

The carburetor described above operates in the following manner:

When the engine is started up, either by the self-starter or by hand, it creates a vacuum in the air admission conduit 8, so that the outside air drawn into this conduit flows towards the engine in an endeavour to fill up this vacuum. The vacuum is also transmitted by way of the tube 11 to the chamber 1, so that a certain vacuum is also set up therein. The fuel in the chamber 1 immediately starts to boil and the fuel vaporizes, thereby filling the free part of the chamber 1 with gasoline vapour. This boiling continues until complete saturation of the space above the surface level of the fuel is attained. The engine, continuing to run, maintains the vacuum in the conduit 8, and the fuel vapour naturally flows through the part 17 and the channel 11 into the conduit 8, where it becomes intermingled with the air passing towards the engine. This explosive mixture enters the cylinders of the engine, and the latter then continues to operate automatically, maintaining a vacuum in the conduit 8.

As the fuel vaporizes in the chamber 1 the surface level of the liquid drops, thus lowering the float 3, which operates the lever 5, causing the latter to pivot about its axis 6 and to liberate the needle valve 4 so as to permit the entry of more fuel by way of the pipe 7 to restore the fuel surface level to its original and normal point. The fuel vaporized is thus replaced progressively and its surface level kept constant in the vaporizing chamber 1.

Furthermore, as the valve 9 is rigidly and positively associated with the obturator 16 through the intermediary of the shaft 10, the result is that when the accelerator opens the valve 9 by means of members 20 and 19 to increase the feed to the engine, the obturator progressively uncovers the port 17 simultaneously, thus permitting the passage of a quantity of fuel vapour proportional to the air sucked in by the engine. This proportion can be predetermined by the external contour of the obturator 16. Thus it is possible, with a suitable obturator and a port 17 of appropriate size, to obtain that mixture of fuel and air which is most perfect and most favourable at all speeds of the engine.

Figs. 3 and 4 show another form of carburetor in which the vaporizing chamber does not contain any fuel. In these figures, the vaporizing chamber 1 is likewise arranged alongside a conduit 8 conveying air to the engine. As in the example according to Figs. 1 and 2, this conduit

contains a butterfly valve 9 mounted on a shaft 10 operated by a lever 19 and a ball and socket joint 20. Beneath the valve 9 there is again a diffuser 13 in the axis of which is located the mouth 12 of a pipe 11 directed towards the engine and communicating by way of a port 17 with the vaporizing chamber 1. The shaft 10 also passes through this chamber, but does not carry a device for closing the port 17, which thus remains continuously open. The shaft 10 has fixed to it a resilient piece of metal or obturator 21 of such form as to permit the port 22 by which the fuel supply pipe enters the chamber 1 to be uncovered. In this case therefore it is not the quantity of the fuel vapour emerging from the vaporizing chamber 1 which is regulated, but the quantity of fuel which is allowed to issue from the pipe 7 and to vaporize in said chamber. In order to prevent droplets of fuel issuing from the pipe 7 from entering the pipe 11 directly by suction, a deflector (not shown) may be placed between the pipe 7 and the port 17 of the pipe 11.

With this construction, the fuel is introduced into the chamber 1 progressively and proportionally to the amount of explosive mixture serving to feed the engine. As the metallic part 21 is shifted simultaneously with the butterfly valve 9 it is possible, by giving this member 21 an appropriate external contour, to regulate the quantity of fuel to be vaporized in accordance with the amount of air sucked in by the engine.

In order to prevent waste of fuel vapor sucked by the engine when the valve 9 is closed suddenly, a second obturator may be provided in the chamber 1 over the port 17 through which this vapor emerges. Such obturator would also be controlled by the operation of the valve 9.

In a third embodiment of the invention shown in Fig. 5 to 7, the apparatus comprises a cylinder 31 (rotating in a box) articulated on a shaft 32 and having a window or slot 33 formed therein. This aperture 33 is variable in depth and width, increasing from the very lowest depth and width up to its maximum.

Against the cylinder 31 there is applied a fibrous part 37 (or this part may be made of any metal different from that of the cylinder 31) which fits exactly with the partial contour of the cylinder and in which is formed a channel 34 for admitting fuel from the pipe 35. This fibrous part 37 is pressed against the cylinder 31 by a spring 39 so as to render the assembly absolutely tight. The fuel liberated by the aperture 33 flows into the vaporizing chamber 40 by way of the channel 45. The movement of the cylinder 31 is synchronized with that of the throttle valve 54 of the carburetor by means of levers 38, 38' and 38'' or by any other suitable means.

The vaporizing chamber indicated at 40 is surrounded by a water chamber 41. The warm water coming from the cylinder head by way of the pipe 42 is evacuated by way of the port 43. A tubular grid 44 of variable delivery, through which pass the hot exhaust gases of the engine, completes the heating arrangement.

A channel 46 coming from the vaporizing chamber 40 opens into the tubular passage 57 by way of which the air flows towards the engine in the direction of the arrow. This channel 46 could be so arranged as to be capable of being advanced or retracted, either mechanically or automatically, in such a way that its outer extremity where it opens into the air passage 57 is always at the place where the best vacuum exists.

A device for regulating the vacuum in the

vaporizing chamber and for regulating the amount of air for supplying the engine is also provided, and is constructed in the following manner:

An obturator 47 composed of two or more lamellae (or in any other appropriate manner, such for example as two hollow concentric cylinders provided with windows and sliding one upon the other) works either like an ordinary diaphragm such as those used in photographic cameras, or else, and as is preferred, in the manner shown in Fig. 6. It is made up of two superimposed plates 47' and 47'' articulated upon an axis 58. These plates are pierced with apertures 59 and 60 of appropriate and determined form, in such a manner that in shifting one over the other they constitute a variable aperture 36 having as its centre the place where the extremity of the gasified fuel supply channel 46 opens. These two plates move in opposite directions and are controlled by levers 61 and 62 pivoting in a connecting rod 48 attached at its other end to a piston 49 moving in a cylinder 50 closed at its opposite end. The piston is urged towards the right by the spring 51, whose pressure is adjustable by means of the screw-threaded plug 52. This cylinder 50 is in communication with the vaporizing chamber 40 by way of the channel 53. A butterfly valve 54 adapted to close the air supply conduit 57 is articulated on the shaft 55, which is controlled by the lever 56 connected with the engine accelerator.

The carburetor just described operates in the following way:

When the engine is stopped, the obturator 47 is quite closed owing to the pressure of the spring 51. The throttle 54 occupies a position that permits the quantity of fuel gas to pass, that is necessary for slow running of the engine.

As soon as the engine is started it sucks the air located behind the throttle 54, the obturator 47 and the air combined in the vaporizing chamber 40. The vacuum created in the latter communicates itself by way of the channel 53 to the cylinder 50. The piston 49 is then drawn towards the left, thus causing the obturator 47 to open. The air entering by way of the channel 57 endeavours to fill up the vacuum existing behind the obturator 47.

From this moment the air drawn in from the exterior by the passage 57 in the direction of the arrow, by its rapid passage past the aperture 36 of the obturator 47, maintains the vacuum existing in the vaporizing chamber 40, in correlation with the suction of the engine.

As the throttle 54 is opened, so does the air-draft of the engine increase, and the vacuum existing at the place where the channel 46 terminates at the aperture 36 of the obturator 47 becomes greater and greater. This vacuum is transmitted to the vaporizing chamber 40, and thence by the channel 53 to the cylinder 50. The piston 47 is thus shifted towards the left, and by means of the connecting rods 48 it widens the aperture 36 of the obturator 47 until equilibrium with the pressure of the spring 51 is reached. The vacuum existing in the chamber 40 and cylinder 50 thus increases with the speed of the engine and widens the aperture 36 of the obturator 47 proportionally.

It will be seen that at the same time as the throttle valve 54 is opened the cylinder 31 is pivoted about its axis through the intermediary of levers 38, 38' and 38'', thus shifting the window 33 over the port 34 and, according to its posi-

tion, liberating the amount of fuel necessary at the existing speed of the engine. This fuel, entering the vaporizing chamber 40 by way of the channel 45, is gasified owing to the vacuum that exists in said chamber, this vaporization being enhanced by the heating grid 44. The calories absorbed by the vaporization of the fuel are then restored by the heating system 44 and the water chamber 41.

10 The fuel thus vaporized is sucked through the channel 46 from which it issues at the aperture 36 of the obturator 47 in the passage 57, where it mixes with the air from the exterior, the explosive mixture thus formed being sucked in by the engine.

15 In addition to the advantages inherent to the preliminary vaporization of the fuel, this construction permits a better charging of the engine cylinders, owing to the fact that it is possible to eliminate the heating of the gaseous fuel and thus give the engine a less expanded gas. The volumetric output of the engine will thus be substantially improved.

20 The obturator 47 could obviously be operated mechanically and independently of the vaporizing chamber by connecting it in appropriate manner to the movement of the throttle 54. The cylinder 50 and its accessories would be suppressed in this case.

25 Figs. 8 and 9 show yet another form of carburetor in which the throttle valve and the obturator form a single mechanically operated unit.

30 The carburetor is here composed of a cylinder 63 pierced by a channel 64 pivoting with slight friction in a box 65 about its axis 32 operated by the lever 38. This box 65 is provided with two windows or apertures co-operating with two channels constituting the air passage 57. The vaporizing chamber is here represented by the hollow cylinder 31 fixed to the cylinder 63 by a nut 66 which permits it to be adjusted. On the exterior of the cylinder 31 there is formed a slot 33 which communicates with the interior by way of the passage 67. From the interior of the vaporizing chamber runs a channel 46 opening into the channel 64. The hot water chamber 41 for restoring the calories absorbed by the vaporization of the fuel, is here arranged in the form of a cover around the cylinder 31 forming the vaporizing chamber. The fuel arrives by way of the channel 35 from which it emerges at the aperture 34 in front of the slot 33.

35 The carburetor just described operates in the following manner:

40 By pivoting the cylinder 63 about its axis, the apertures of the air passage 57 are opened proportionally and at the same time the slot is shifted relatively to the aperture 34, thus increasing the delivery of fuel proportionately. The air sucked in from outside in the direction of the arrow creates a vacuum in the channel 46 by its rapid passage in the channel 64. This vacuum is transmitted to the vaporizing chamber 40, thus sucking the fuel liberated by the slot and aperture system. The vaporized fuel escapes at the end of the channel 64 where it becomes mixed with the air entering from outside, thus forming the explosive mixture for feeding the engine.

45 It is easy to see the great advantages of this method of obtaining a gaseous mixture by preliminary vaporization of the fuel before it is mixed with the air. The explosive mixture no longer contains liquid fuel in the form of tiny droplets, a phenomena which could not be completely eliminated in the previously existing apparatus. The

explosive mixture formed by preliminary vaporization is perfect and can be adapted exactly to the different speeds of the engine, it being of course well-known that the mixture should not be the same for all speeds. There is consequently a substantial economy of fuel with an equivalent performance of the engine, in as much as the apparatus prevents incomplete combustion of droplets of fuel which were present in all the gaseous mixtures produced heretofore.

The apparatus devised for carrying out the process according to the invention is of great simplicity and of cheap construction. It permits perfect regulation by suitably shaping the exterior edge of the obturator controlling either the delivery of fuel vapour or the arrival of liquid fuel.

The employment of a carburetor of the kind described permits the complete avoidance of those "stoppages" that are so frequent an occurrence at present, and which are due to the nozzles of the carburetor becoming blocked up with particles of dirt, which are sometimes very small in size.

Finally, owing to the elimination of incomplete combustion of droplets of fuel, there is practically no fouling of the parts of the engine in contact with the explosive mixture. It is evident that a carburetor of the kind described could, if desired, be finished off with certain accessory devices, such for example as the devices, for heating the liquid fuel so as to restore the calories absorbed by the vaporization and to maintain the vaporizing chamber at a temperature permitting more rapid vaporization of the fuel. Finally, owing to its simple and rational manner of operation, a carburetor of the kind described can be used for all kinds of liquid fuels, (petrol, benzole, etc.) without necessitating any modification of the apparatus other than the installation of the obturator which is most appropriate to the fuel employed.

What we claim is:

1. A charge forming device, comprising a vaporizing chamber provided with an inlet port for liquid volatile hydrocarbon, the cross-section of said chamber considerably exceeding that of said port, a conduit adjacent said chamber, the opposite ends of which respectively are adapted to be placed in communication with a suction creating device and with atmosphere, means creating a sub-atmospheric pressure within said chamber and withdrawing volatilized hydrocarbon therefrom, said means comprising a pipe, one end of which communicates with said chamber and the other end of which is positioned within said conduit with the open end thereof directed toward the means for connecting said conduit with the suction creating device, an adjustable obturator in said conduit rearwardly of the open end of said pipe to vary the air flow cross-section of said conduit and means for delivering a supply of liquid volatile hydrocarbon to said vaporizing chamber at such a rate that no substantial liquid level is maintained in the vaporizing chamber.

2. A charge forming device, comprising a vaporizing chamber provided with an inlet port for liquid volatile hydrocarbon, the cross-section of said chamber considerably exceeding that of said port, a conduit adjacent said chamber, the opposite ends of which respectively are adapted to

be placed in communication with a suction creating device and with atmosphere, means creating a sub-atmospheric pressure within said chamber and withdrawing volatilized hydrocarbon therefrom, said means comprising a pipe, one end of which communicates with said chamber and the other end of which is positioned within said conduit with the open end thereof directed toward the means for connecting said conduit with the

10 suction creating device, an adjustable obturator in said conduit rearwardly of the open end of said pipe to vary the air flow cross-section of said conduit, a throttle valve in said conduit forwardly of the open end of said pipe, means for 15 delivering a variable supply of liquid volatile hydrocarbon to said vaporizing chamber, and a linkage connecting said throttle with said regulating means to increase the amount of liquid volatile hydrocarbon supplied to said vaporizing 20 chamber, as the throttle is opened, at such a rate that no substantial liquid level is maintained in said vaporizing member.

3. A charge forming device, comprising a vaporizing chamber provided with an inlet port for liquid volatile hydrocarbon, the cross-section of said chamber considerably exceeding that of said port, a conduit adjacent said chamber, the opposite ends of which respectively are adapted to be placed in communication with a suction creating device and with atmosphere, means creating a subatmospheric pressure within said chamber and withdrawing volatilized hydrocarbon therefrom, said means comprising a pipe, one end of which communicates with said chamber and the other end of which is positioned within said conduit with the open end thereof directed toward the means for connecting said conduit with the suction creating device, a throttle valve in said conduit, a throttle valve operating lever, 40 a cylindrical casing provided in its cylinder wall with an inlet and an outlet passage for liquid volatile hydrocarbon, said outlet passage being connected with the inlet port of said chamber, a solid cylinder fitted rotatably in said casing and being provided with a peripheral groove connecting said inlet and outlet passages, said groove having a peripheral length exceeding the peripheral distances between said two passages and a cross-section increasing from one end to the other of said groove, a lever to adjust said cylinder for admission of a greater or smaller quantity of liquid volatile hydrocarbon into said groove, and a link connecting said throttle valve operating lever with said cylinder adjusting lever to increase the amount of liquid volatile hydrocarbon supplied to said chamber, as the throttle is opened, at such a rate that no substantial liquid level is maintained in said vaporizing chamber.

60 4. A charge forming device, as claimed in claim 3, in which the part of said cylinder casing including said inlet passage is formed as a separate movable member of substantially soft material and resilient means are provided to press said member slightly against said solid cylinder.

5. A charge forming device, as claimed in claim 1, including means to adjust said obturator in dependence upon the subatmospheric pressure created in said flash vaporizing chamber.
